CATHODE FOR DISCHARGE DEVICES

John W. Marden, East Orange, N. J., assignor, by
mesne assignments, to Westinghouse Electric
and Manufacturing Company, East Pittsburgh,
Pa., a corporation of Pennsylvania

Application June 14, 1933, Serial No. 675,671

7 Claims. (Cl. 250—27.5)

This invention relates to glow discharge lamps and relates more particularly to an electrode for a discharge device such as shown and described in copending application Ser. No. 437,659 filed 5 March 21, 1930 and assigned to the same assignee as the present invention.

The above mentioned application shows and describes a device in which two thermionically active electrodes are provided and wherein the 10 difference of potential is produced between the electrodes and means are furnished to heat the electrodes to electron emission temperature to produce a glow discharge. The electrodes are enclosed in a sealed envelope containing an ionizable medium and each electrode is provided with 15 a pair of conductors to permit a flow of electrical energy for heating the electrodes to electron emission temperature to produce a glow discharge which is maintained by the flow of current across the discharge.

20 In the device above outlined a cathode or electrode is provided which consists of a mandrel having a helical winding of a wire which is coated with a thermionically active material. The entire electrode is heated directly by a flow of electrical energy.

It is an object of the present invention to provide an improved form of cathode for a discharge device in which the electron emitting material is 25 heated directly.

Another object of the invention is to provide a cathode for a discharge device comprised of an inner and an outer metallic coil.

Another object of the invention is to provide 30 an indirectly heated cathode comprised of a helical carrier for a thermionically active material.

Another object of the invention is to provide a method of making a cathode of the indirectly heated type.

40 Other objects and advantages of the invention will be apparent from the following description together with the accompanying drawing in which

Fig. 1 is a side elevational view of a pair of 45 cathodes constructed in accordance with the present invention mounted in a bulb;

Fig. 2 is an enlarged view of the cathodes taken in line II—II in Fig. 1;

Fig. 3 is a perspective view of the heater element of a cathode showing a wire connected thereto ready to be coiled about the cathode and

Fig. 4 is a perspective view of a forming mandrel for holding the heater coil and for forming the outer winding therearound.

55 A cathode constructed in accordance with the

present invention may comprise a heater coil 10 having an enclosing helical winding or support 11 for a thermionically active material.

The heater may be a helically wound wire which is again wound to provide what may be 5 termed a coiled coil. The outer coil may be made by welding or otherwise securing an end 12 of a wire 13 to a terminal of the coiled coil. The heater element may, however, be in the form of a straight length of helically coiled filament or 10 may be an uncoiled wire of suitable resistance.

In accordance with the present showing the coiled coil may then be positioned in a forming mandrel 14 having a core 15 to receive the coiled coil and a slot 16 through which the wire 13 15 may extend. When the coiled coil is in position in the mandrel 14 the wire 13 may be wound about the mandrel as shown in Fig. 4 until an outer helical coil is formed. If desirable, the outer surface of the mandrel 14 may be provided 20 with a helical groove or thread to serve as a guide for winding the outer coil to regulate the spacing thereof.

Cathodes constructed in accordance with the present invention may be mounted in a discharge 25 device and, as shown in Fig. 1, such device may comprise a bulb 17 sealed at 18 to a flare tube 19 having a press 20 and containing a suitable ionizable medium; as for example mercury vapor. Lead wires 21, 22 may be sealed in the press and 30 extend into the bulb to serve as supports for the cathodes. A cathode may be secured to the supports by having one end of the coiled coil electrically connected to one support and the free end of the outer coil secured to the other support. 35 Connection between the coiled coil may be made prior to the operation of winding the outer coil as shown in Fig. 3. It is to be understood however that a cathode may be constructed by making the coiled-coil heater and the outer winding 40 as separate parts and in subsequently welding or otherwise securing the parts together.

The outer coil may be made of about 20 to 31 mil nickel, nickel wound tungsten, Monel or other suitable base metal. The heater or coiled coil 45 may be of tungsten.

When the cathode is to be used in a lamp having a drop of about 15 volts the heater element 10 may consist of a non-sag tungsten space wound coil wound on a 21 mil mandrel with about 125 50 turns per inch. The wire may be of a weight of from 21 to 22½ milligrams per 200 m. m. of length. The heater element may consist of 15 m. m. coil length including about 75 turns of wire 55 wound as above described. When winding the

outer coil the mandrel on which this coil is wound may be about 180 mils in diameter.

For the purpose of providing an electron emitting surface the outer coil may be sprayed or otherwise coated with a quick drying binder such as nitrocellulose in amylacetate, with the carbonates of the alkaline earth metals. The carbonates are stable in atmosphere and may be stored for indefinite periods without detrimental effects. After the cathode assembly has been mounted within the bulb the carbonate coating is converted to the oxides of the alkaline earth metals by heating the cathode to a sufficiently high temperature. The method of providing a cathode with an electron emissive material, as above briefly given, is known in the art and may be varied to meet attending conditions.

It has been found that there are no detrimental results if the heater receives some of the electron emissive material when the outer coil is sprayed since this deposit on the cathode is burned off when the heater reaches a high temperature upon a flow of current.

The present invention provides an improved and simple cathode assembly for use in discharge lamps where it is desirable to support a thermionically active material for indirect heating. The structure shown may be constructed with a minimum amount of labor and at relatively low cost.

Although a preferred embodiment of the invention is shown and described herein it is to be understood that modifications may be made therein without departing from the spirit and scope of the invention as set forth in the appended claims.

What is claimed is:

1. An electric discharge lamp comprising a bulb, a press at one end of said bulb, a pair of electrodes disposed in parallel spaced relation, each of said electrodes including a pair of rigid support members extending from said press, a rigid helical coil having one end secured to one of said support members, a coating of electron emission material on said coil, another double helically coiled wire having one end secured to the other support wire and the other end secured to and supported on the free end of said rigid coil.
2. An electric discharge lamp comprising a bulb, a stem extending from one end of said bulb, a pair of elongated electrodes disposed in parallel spaced relation, each electrode including a pair of support wires secured in said press, a rigid helical coil having one end secured to one of said support wires and a less rigid coiled coil supported in concentric relation to said rigid coil by the other support wire and held by the free end of said rigid coil.
3. An electric discharge lamp comprising a bulb, a stem extending from one end of said bulb, a pair of elongated electrodes disposed in parallel spaced relation, each electrode including a pair of support wires secured in said press, a rigid helical coil having one end secured to one of said support wires and a less rigid coiled coil supported in concentric relation to said rigid coil by the other support wire and held by the free end of said rigid coil.

lel spaced relation, each electrode including a pair of support wires secured in said press, a rigid helical coil having one end secured to one of said support wires and a double helical coil disposed within and supported in concentric relation to said rigid coil by the other support wire and held in spaced relation to said rigid coil by the other end of said rigid coil.

4. A discharge lamp comprising a bulb, an ionizable medium within said bulb, a pair of electrodes disposed within said bulb and positioned in relatively close parallel spaced relation to produce a glow discharge therebetween when subjected to a voltage drop of sufficient potential, each of said electrodes comprising a rigid helical coil having a thermionically active material thereon, a conductive support member secured to one end of said rigid coil, a heater coil having one end secured to the other end of said rigid coil and another conductive support member connected to the other end of said heater coil, said conductive support members serving to permit a flow of electrical energy through said heater coil to heat said rigid coil and cause an electron flow by reason of a potential difference between said electrodes, said electron flow causing an ionization of the gas to produce a glow discharge.

5. An electrode for a discharge device comprising a rigid helical coil having thereon a coating of thermionically active material, two rigid support members, said coil having one end secured to one of said rigid support members, a flexible coil for heating said material, said coil having one end secured to the other rigid support member and the other end secured to and supported by the other end of said rigid helical coil.

6. An electric discharge lamp comprising a bulb, an ionizable medium in said bulb, a press at one end of said bulb, a pair of rigid support members extending from said press, a rigid helical coil having one end secured to one of said support members, a coating of electron emission material on said coil, another helical coil concentrically disposed within and disposed in spaced relation to said rigid coil for the passage of said medium between said coils, said other helical coil having one end connected to the other support member and the other end connected to and supported by the other end of said rigid coil.

7. An electric discharge lamp comprising a bulb, a stem extending from one end of said bulb, a pair of support wires secured in said press, a rigid helical coil having one end secured to one of said support wires, a coating of emission material on said coil and a coiled coil connected to the other support wire and held in spaced relation to and substantially on the longitudinal axis of said rigid coil by the other end of said rigid coil.

JOHN W. MARDEN.
